UNITED STATES PATENT OFFICE.

OSCAR HAMMERSTEIN, OF NEW YORK, N. Y.

CIGAR-BUNCH-ROLLING MACHINE.

No. 872,125.

Specification of Letters Patent.

Patented Nov. 26, 1907.

Original application filed June 25, 1904, Serial No. 214,082. Divided and this application filed August 10, 1906. Serial No. 329,979.

To all whom it may concern:

Be it known that I, OSCAR HAMMERSTEIN, a citizen of the United States, residing in the borough of Manhattan, city, county, and 5 State of New York, have invented certain new and useful Improvements in Cigar-Bunch-Rolling Machines, of which the following is a specification.

This application is a division of my application No. 214,082, filed June 25, 1904.

My invention relates to cigar bunch rolling machines and has for its object to produce an apparatus in which the operations essential to the rolling of a cigar bunch may be performed in proper sequence and at the proper time interval. This object I achieve by means of the mechanism shown in the accompanying drawing which shows one form of my invention. It will be obvious however that my invention is not limited to the apparatus shown.

In the drawing: Figure I is a perspective view of the machine:—Fig. II is a plan view of Fig. I broken away to clearly show the operating parts for the rolling mechanism:—Fig. III is a sectional side elevation of the machine, the section being taken through the table. The parts are here shown in the positions that they assume when the apron 30 is ready to receive the bunch. Fig. IV is a fragmentary view similar to Fig. III showing the bunch in place:—Fig. V is a similar view showing the cross bars rollers or jaws as I shall hereinafter call them brought together 35 and before the apron has been tightened to its full extent:—Fig. VI shows the parts during the next stage of the operation wherein the apron has been drawn taut and the rolling is completed with the rollers or jaws in 40 the position shown in said figure:—Fig. VII shows the parts during the next stage of the operation where the jaws have been automatically opened as will be explained so as to permit the removal of the bunch from the 45 apron:—

In the drawing *a* represents a table of any desired or preferred construction. Bracket *m* secured to the said table serves to support the operating parts of the machine. This 50 bracket *m* serves to support a cross-bar *r*. An apron *o* is connected at one end *p* and at the other end *q* to the cross-bar *r*, which cross-bar is adapted to be moved over the arc shaped portion *s* of the bracket *m*, said 55 arc shaped portion being provided at either

extremity with suitable stops *t*. Fixed rollers *u*, over and around some of which the apron *o* passes are also supported from the bracket *m*.

The actuating mechanism for the cross-bar comprises an arm *v* pivoted at *w* and having abutments *z* to engage the cross-bar *r*. The arm *v* may be swung by a foot-piece *x*, the counter-balance weight *y* being connected to the pivotal point *w* in order to aid in restoring the parts to their initial positions shown in Figs. I, II and III.

The uppermost rollers, herein shown as a fixed roller *u* and a movable roller *u'*, constitute jaws for insuring the compression of the bunch after it has been placed in the bight *l* of the apron and to assist in rolling the bunch. These rollers or jaws are carried respectively as follows:—One roller *u* is carried by the bracket *m* and the other roller *u'* is carried on an arm *2* which is pivoted at *3* and provided with a roll *4* entering a cam slot *5* in the arm *v*, which slot *5* is of special construction to effect the operations incident to efficient rolling all in proper time, that is to say, to bring the jaws together at the proper time, to time and regulate the tightening of the apron as to produce the best results, and to release the tension and open the jaws at the proper time. The special construction of this cam will be set forth hereinafter in describing the detailed operation of the machine.

In addition to mechanism for imparting a swinging movement, as hereinafter described, to the roller or jaw *u'*, means are provided for tightening the apron so as to insure the efficient operation of the machine. The means for tightening the apron comprises a belt tightening roller *7* mounted upon an arm *8* pivoted at *9* and provided with a roll *10* entering the cam slot *5* of the arm *v*. A weight *11* is provided pivoted at *12* for the purpose hereinafter mentioned to constitute a locking nose.

It will be readily understood that swinging the arm *v* will cause the cam slot *5* to act upon the rolls *4* and *10* to operate the jaws and the tightening device. It will also be obvious that movement of the cam *5* will effect these movements but the most important feature is the timing of the movements. It is desirable that the jaws or rollers be closed or brought together and a movement of the apron initiated before the final

tightening of the apron takes place. This is accomplished by the peculiar shape of the cam slot 5. It will be observed that this slot is constituted of cam surfaces 5^a , 5^b , 5^c , 5^d , to impart the various movements in proper time. These movements are effected as follows: Starting with the parts in the position shown in Figs. III and IV, with the bunch 18 and binder 19 in place, the first effect of the movement of the cam 5 will be to bring the roll 4 operating the movable jaw or roller u' into the portion 5^b of the cam 5, thus bringing the movable jaw or roller in proximity to the fixed jaw or roller to close the loop in the apron. At the same time a slight tightening of the apron is effected as the roll 10 governing the tension of the apron moves over the cam portion 5^a of the cam 5 and is about to enter cam portion 5^b of the said cam. At this instant the roller 10 enters the cam portion 5^b and as the movement of the cam continues the roller 10 traverses the portion 5^b of the cam and firmly tightens the apron. It will be understood that after the closing of the jaws and during the slight preliminary tightening and before the final tightening the apron o has begun to move. This movement of the apron is brought about by the engagement of the left-hand abutment z with the cross-bar r . It is desirable that the final tightening should not take place until the rolling operation is initiated, as such tightening would cause the rollers u , u' to bind and the result would be unsatisfactory. It is for this reason that the cam surfaces 5^a and 5^b are arranged as shown. The parts have now assumed the positions shown in Fig. VI wherein the rollers 4 and 10 are shown as traversing the portion 5^c of the cam and the rolling of the bunch is being effected.

The cam continues to move and the rollers finally come into the positions shown in Fig. VII wherein the roller 4 is shown as having run into the portion 5^d of the cam and resting behind the weighted cam latch 11, while the roller 10 rests beneath the latch 11. The effect of these last mentioned movements is to separate the jaws or rollers and to permit the removal of the bunch from the machine. It will thus be observed that the cam 5 effects the following operations viz:—a closing of the jaws, accompanied by a slight tightening of the apron; then the apron begins to move and is subjected to further tension; and finally there is an opening of the jaws and release of the tension at the completion of the rolling operation. These operations are all performed automatically and harmoniously owing to the peculiar shape of the cam.

Having described my invention, what I claim and desire to secure by Letters Patent is:—

1. The combination of a frame having a guide, a bar movable back and forth on said

guide, an apron the ends of which are secured to opposite sides of said bar, fixed rollers and a movable roller over which said apron passes to form a bight between said movable roller and one of the fixed rollers, an operating member having projections adapted to engage said bar on opposite sides, the distance between the projections being greater than the width of the bar so that the operating member will have a partial movement independently of the bar, and means for actuating the movable roller by the independent movement of the operating member. 70 75

2. The combination of a frame having a guide, a bar movable back and forth on said guide, an apron secured to said bar so as to move therewith, means for supporting the apron, an operating member movable in the same direction as the said bar and adapted to engage it on opposite sides, but capable of a partial movement independently of said bar, and bight-opening and closing means actuated by said independent movement of the operating member. 80 85

3. The combination of a frame having a guide, a bar movable back and forth on said guide, an apron secured to said bar so as to move therewith, means for supporting the apron, an operating member movable in the same direction as the said bar and adapted to engage it on opposite sides, but capable of a partial movement independently of said bar, a tension device for said apron, actuated by the movement of the operating member, and bight-opening and closing means actuated by 90 95 100 said independent movement of the operating member.

4. The combination of a frame having a guide, a bar movable back and forth on said guide, an apron secured to said bar so as to move therewith, means for supporting the apron, an operating member movable in the same direction as the said bar and adapted to engage it on opposite sides, but capable of a partial movement independently of said bar, 105 110 115 a tension device for said apron, means for applying said tension device slightly during the initial independent movement of the operating member and more strongly when said operating member moves together with the apron bar, and bight-opening and closing means actuated by said operating member.

5. The combination of a frame having a guide, a bar movable back and forth on said guide, an apron secured to said bar so as to move therewith, means for supporting the apron, an operating member movable in the same direction as the said bar and adapted to engage it on opposite sides, but capable of a partial movement independently of said bar, 120 125 a tension device for said apron, means for applying said tension device slightly during the initial independent movement of the operating member and more strongly when said operating member moves together with the 130

apron bar, and bight-opening and closing means actuated by said independent movement of the operating member.

6. The combination of the operating member having spaced actuating projections, the rolling apron provided with a rigid member adapted to be engaged by either of said projections, means for supporting the apron, and bight-opening and closing means actuated 10 by the operating member before its projection engages the rigid apron member.

7. The combination of the rolling apron and means for supporting it, the operating member for actuating said apron but capable 15 of a movement independently thereof, and bight-closing and opening means actuated by the independent movement of the operating member.

8. The combination of the rolling apron 20 and means for supporting it, the operating member for actuating said apron but capable of a movement independently thereof, a tension device for said apron, actuated by the movement of the operating member, and 25 bight-opening and closing means actuated by said independent movement of the operating member.

9. In a cigar bunch rolling machine, the combination of an apron, rollers coöperating 30 therewith, a tightening device and a cam 5 having the cam surfaces 5^a 5^b, for moving a roller and bringing the tightening device into action gradually, after the rollers have gone into action.

10. The combination of the rolling apron 35 and means for supporting it, the operating member for actuating said apron but capable of a movement independently thereof, a tension device for said apron, means for applying said tension device slightly during the 40 initial independent movement of the operating member and more strongly when said member moves in unison with the apron, and bight-opening and closing means actuated by said operating member. 45

11. The combination of the rolling apron and means for supporting it, the operating member for actuating said apron but capable 50 of a movement independently thereof, a tension device for said apron, means for applying said tension device slightly during the initial independent movement of the operating member and more strongly when said member moves in unison with the apron, and bight-opening and closing means actuated 55 by said independent movement of the operating member.

12. In a bunch rolling machine, the combination of an apron, rollers coöperating therewith and a cam 5 for closing the rollers 60 and having the lateral portion 5^d to open the rollers apart at the close of the rolling operation.
